(57) CLAIM

I claim the ornamental design for footwear, as shown and described.

DESCRIPTION

FIG. 1 is a perspective view of footwear, showing my new design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a back view thereof.

The unevenly spaced dashed lines are included for illustrating environmental structure and form no part of the claimed design. The evenly spaced dashed lines represent stitching which also forms no part of the claimed design.
